FURNACE GRATE BAR CONSTRUCTION

Filed Oct. 26, 1928

UNITED STATES PATENT OFFICE

HARRY W. NEAL, OF INDIANAPOLIS, INDIANA, ASSIGNOR TO HALL-NEAL FURNACE COMPANY, OF INDIANAPOLIS, INDIANA

FURNACE-GRAVE-BAR CONSTRUCTION

Application filed October 26, 1928. Serial No. 315,137.

This invention relates generally to furnaces and in particular to a grate bar mounting having for its primary object the provision for the quick and easy removal and replacement 5 of grate bars in a simple and inexpensive manner without the necessity of having to dismantle the fire pot or bowl of the furnace or the wall of the furnace in any manner. Other objects reside in the provision made 10 for warping of the bars, interchangeable means for rocking a selected number of the bars at one time in shaking down ashes and for means in retaining the various parts in alignment.

15 The invention is described in reference to the accompanying drawing, in which—

Fig. 1 is a front elevation of a house heating furnace embodying my invention;

Fig. 2, a transverse horizontal section 20 through the furnace on the line 2—2 in Fig. 1;

Fig. 3, a vertical section on the line 3—3 in Fig. 2;

Fig. 4, a longitudinal vertical section on the line 4—4 in Fig. 2 showing the grate bar 25 in side elevation;

Fig. 5, a vertical section on the line 5—5 in Fig. 2; and

Fig. 6, a vertical section on the line 6—6 in Fig. 5.

30 Like characters of reference indicate like parts throughout the several views in the drawing.

Within the body 10 of the furnace is mounted the horizontal grate ring 11, from the 35 under side of which are supported the grate bars 12, 13, 14, and 15. Each bar has a reduced cylindrical section loosely fitted through respective rear bearings 16, 17, 18, and 19, and also has a reduced cylindrical section 22 passed between two ribs 20 and 21 (Figs. 2 and 5) which section 22 rests on a lug 23 which removably slips against the forward faces of the ribs 20 and 21 and drops down into pockets 24 and 25.

40 Each of the bars 12, 13, 14 and 15 has a shoulder 26 formed on it from which extends forwardly a three-sided shank 27, to carry with a loose sliding fit thereon a gear 28 having an extending hub 29. As indicated in Fig. 2, the gears 28 on the bars 12 and 13 are

in mesh and have their respective hubs 29 turned to bear against the shoulders 26, while the gears 28 on the bars 14 and 15 are in mesh and with their respective hubs 29 turned outwardly, whereby rocking the bar 12 will rock 55 the bar 13, and rocking the bar 15 will rock the bar 14, the bars thereby being interconnected through the gears 28 in pairs. It is obvious that the gears 28 on the bars 14 and 15 may be reversed in position, in which reversed position all four gears 28 would mesh consecutively one with the other (not shown) and the rocking of any one bar could rock the other three.

Now to prevent the gears 28 from sliding 65 out of mesh or off the shanks 27, I place a plate 30 over the ends of the shanks 27 and against the gears, the plate 30 having holes suitably spaced to permit the shanks 27 to extend freely therethrough (Fig. 3).

70 A stub shaft 31 has a socket 32 to fit loosely over the end of the shank 27 on the bar 12 and against the plate 30.

The shaft 31 extends forwardly through a hole 33 in the front wall casting 34 of the furnace and has a reduced three sided shank 35 extending rotatably through a retaining plate 36 which is held in place by the bolts 37 and 38. The usual shaker bar (not shown) is fitted over the shank 35 to rock the two bars 12 and 13. A similar shaft 39 fits over the end of the shank 27 of the bar 15 and against the plate 30 and has a reduced shank 40 extended through the plate 41. Since the plates 36 and 41 prevent the shafts 31 and 39 from 85 sliding forward the gears 28 are effectively held on the shanks 27 through the intervening plate 30. All of the parts are fitted one to the other rather loosely to allow for expansion and warping. Since the forward ends 90 of the bars rest entirely on the lugs 23, any normal warping of the bars will not affect their being turned. The sockets on the ends of the shafts 31 and 39 being fitted loosely also permit of considerable misalignment before 95 any binding will occur.

To remove a grate bar, the plates 36 and 41 are taken off whereupon the shafts 31 and 39 are pulled out through the casting 34, the plate 30 is slipped off the shanks 27, the gear 100

28 removed from the bar to be moved. Any one of the bars 12, 13, 14 or 15 may therefore be readily removed without tools by simply lifting the front end of the bar, raising and 30 removing the lug 23, and lowering the front end from between the ribs and pulling the bar forward to disengage it from the rear bearing, the bar being replaced in reverse manner.

I claim:

- 10 1. In a furnace, a grate bar removably carried in the furnace, a shank on the forward end of the bar, a gear slidably carried on the shank but fixed to rotate therewith, a shaft having a socket adapted to fit over the end of 15 the shank extending through said gear, a removable plate on said furnace, through which said shaft extends, and a shoulder on said shaft bearing against said plate whereby said shaft socket is held on said shank.
- 20 2. In a furnace, a grate bar, a bearing in which the rear end of the bar is rotatably supported, a pair of spaced apart ribs between which the front end of the bar passes, and a lug removably carried adjacent and across 25 the opening between said ribs under said bar, a shank on the forward end of the bar, a gear slidably carried on the shank but fixed to rotate therewith, a shaft having a socket adapted to fit over the end of the shank extending 30 through said gear, a removable plate on said furnace, through which said shaft extends, and a shoulder on said shaft bearing against said plate whereby said shaft socket is held on said shank.
- 35 3. In a furnace, a plurality of grate bars supported in the furnace, a shank on the forward end of each bar, a gear carried on each shank adapted to slide longitudinally thereon but fixed to rotate therewith, a retaining 40 plate having holes to permit the ends of the shanks to extend therethrough, a furnace wall, shafts passing through holes in said wall and having sockets in their inner ends fitting over ends of selected bar shanks to 45 retain said plate against said gears, plates removably attached to said wall over said holes and supporting the front ends of the shafts, and shoulders on said shafts bearing against said plates whereby said shafts are 50 prevented from sliding forwardly off the shanks.
4. In a furnace, a plurality of grate bars rockably supported therein, a shank on the forward end of each bar, a gear on each shank 55 slidably longitudinally thereon but fixed to rotate therewith, a spacing hub on each gear, said gears being positioned on said shanks whereby the hub on adjacent gears are turned one way and on other gears are turned in the 60 reverse direction to have the gears meshed in separate groups, a retaining plate having the ends of the shanks extending rotatably therethrough, shafts having sockets formed in their inner ends to engage over the shank ends, a 65 furnace wall, one of said shafts having its

socket end carried on a bar shank in each of said gear groups and extending axially through a hole in said wall, a cover plate removably positioned over each hole, said shafts extending through and their front ends supported by said cover plates, and a shoulder on each of said shafts behind said cover plates limiting the longitudinal movement of the shafts whereby the retaining plate is held across the shanks against said 75 gears and gear hubs.

5. In a furnace, a grate bar construction comprising a plurality of grate bars each having its rear end carried in a bearing and the front end movable vertically between 80 spaced apart ribs with a removable lug between said ribs limiting the downward movement, gears reversably and slidably carried on shanks of the bars ahead of said ribs, a gear retaining plate across the forward sides 85 of the gears, a shaft removably extended from the ends of selected shanks which extend through said gears and said plate, and other plates removably secured on the furnace through which said shafts rotatably pass and 90 by which longitudinal travel of the shafts from the shanks is prevented.

In testimony whereof I affix my signature.
HARRY W. NEAL.
